(57) **CLAIM**

The ornamental design for a rear cover for motor scooter, as
shown and described.

DESCRIPTION

FIG. 1 is a perspective view from the front side of a rear cover
for motor scooter.

FIG. 2 is a perspective view from the front side thereof.

FIG. 3 is a perspective view from the rear side thereof.

FIG. 4 is a perspective view from the rear side thereof.

FIG. 5 is a front elevation view thereof.

FIG. 6 is a rear elevation view thereof.

FIG. 7 is a top plan view thereof.

FIG. 8 is a bottom plan view thereof.

FIG. 9 is a right side elevation view thereof.

FIG. 10 is a left side elevation view thereof; and,

FIG. 11 is a referential view showing use thereof.

The portions of the rear cover for motor scooter and other
portions of a motor scooter shown in broken lines are for the
purpose of showing environmental structure only and form no
part of the claimed design.
